UNITED STATES PATENT OFFICE.

ANNIE M. POND, OF NEW YORK, N. Y., ASSIGNOR TO ORDER OF THE EASTERN STAR
STATE OF NEW YORK, OF NEW YORK, N. Y., A CORPORATION OF NEW YORK.

DESIGN FOR AN EMBLEM OR BADGE.

58,045.

Specification for Design.

Patented May 31, 1921.

Application filed August 5, 1920. Serial No. 401,519. Term of patent 14 years.

To all whom it may concern:

Be it known that I, ANNIE M. POND, a citizen of the United States, residing at Masonic Temple, 23rd street and 6th avenue, in the borough of Manhattan, city, county, and State of New York, have invented a new, original, and ornamental Design for an Emblem or Badge, of which the following is a specification, reference being had to the accompanying drawing, forming part thereof.

The figure is a view of an emblem or badge showing my new design.

I claim:

The ornamental design for an emblem or badge, as shown.

ANNIE M. POND.
